CIGAR LIGHTER

Albert Edward Pollock, New York, N. Y.

Application April 13, 1954, Serial No. 29,982

Term of patent 3½ years

(Cl. D48—27)

FIG. 1.

FIG. 2.

Fig. 1 is a side perspective view of a cigar lighter showing my new design; and

Fig. 2 is a perspective view showing the side opposite Fig. 1.

I claim:

The ornamental design for a cigar lighter, as shown.
